UNITED STATES PATENT OFFICE

SAMUEL SEGAL, OF NEW YORK, N. Y., ASSIGNOR TO SEGAL LOCK & HARDWARE COMPANY, INC., OF NEW YORK, N. Y., A CORPORATION OF NEW YORK

LOCK

Application filed August 4, 1925. Serial No. 48,019.

This invention relates to an improved type of lock.

It is an object of the invention to provide a lock in which the parts are so constructed and arranged that if a forcible opening thereof is attempted, the parts, although resisting such opening, will not be liable to become distorted so as to subsequently not function.

10 A still further object is that of furnishing a device of this character the parts of which may be easily and cheaply manufactured and assembled and in which the finished lock may be readily operated in a positive manner 15 and with freedom from mechanical difficulties.

Specifically, it is another object to present a lock of the rotatable bolt type, which lock will be acceptable from a commercial stand- 20 point.

The invention accordingly comprises the features of construction, combination of elements and arrangement of parts which will be exemplified in the construction hereinafter 25 set forth, and the scope of the application of which will be indicated in the claims.

For a fuller understanding of the nature and objects of the invention reference should be had to the following detailed description 30 taken in connection with the accompanying drawings, in which:

Fig. 1 is a side elevation of one form of lock embodying one form of the present invention and showing the parts in retracted 35 position;

Fig. 2 is a similar view with the parts projected;

Fig. 3 is an end view of the lock as shown in Fig. 1;

40 Fig. 4 is a transverse sectional view taken along the lines 4—4 and in the direction of the arrows in Fig. 1;

Fig. 5 is a view similar to Fig. 1 but showing a slightly different form of lock structure;

Fig. 6 is a fragmentary partly sectional plan view taken along the lines 6—6 and in the direction of the arrows in Fig. 5;

50 Fig. 7 is a fragmentary end view of the lock shown in the two preceding figures;

Fig. 8 is a view corresponding to Figs. 1 and 5 and showing still another form of lock constructed within the terms of the present invention;

Fig. 9 is a transverse sectional view taken along the lines 9—9 and in the direction of the arrows in Fig. 8;

Fig. 10 is a side elevation of a still further form of lock and showing the parts therein in retracted position;

Fig. 11 is a similar view but showing the parts projected;

Fig. 12 is a partly sectional plan view of the mechanism as shown in Fig. 10; and

Fig. 13 is a transverse sectional view taken along the lines 13—13 and in the direction of the arrows indicated in Fig. 10.

In these several views the numeral 15 indicates the lock case, which may be in the form of a receptacle having an open side 70 face normally closed by a conventional cover-plate. The forward edge of the case is in each instance formed with a slot 16 for the passage of the bolt or bolts, and these latter, in the present exemplification, include a pair 75 of shafts 17 having their outer ends headed as at 18, it being noted that these heads are oblong and preferably of such shape that in one position they may be retracted to a point within the slot 16 so that their outer faces 80 lie in substantially the same plane as the outer edge of the case.

These bolts are operatively supported in each form of lock by a bolt carrier which has a forked rear end 19, the arms of this fork straddling a shaft 20 rotatably mounted by the case. A crank 21 is attached to the shaft and pivotally carries at its outer end one end of a curved link 22, the opposite end of which is pivotally attached as at 23 to the bolt carrier, it being understood that these latter parts lie in a plane beyond the forked end 19.

Thus it will be understood that in each instance, upon the shaft 20 being turned the carrier will be projected and retracted, together with the bolts supported thereby, and at this time it will be noted that the forked ends 19 of these carriers are each preferably provided with a ledge 24, which, when the parts are in the positions shown in Figs. 100

2 and 11, will be engaged by the lower edge of the crank 21.

In order to properly associate the bolts with the carriers, the latter are formed with rightangle extensions 25 adjacent their forward edges, these extensions being provided with openings corresponding in number and size to the number and size of the bolts utilized. The shanks of these latter elements are passed through these openings and have their inner ends projecting beyond the inner faces of the extensions 25, and at this point are formed with reduced portions 26 providing grooves into which a locking plate 27 may fit in order to prevent any movement other than rotative on the part of the bolts with respect to the carriers.

With specific reference to the type of lock shown in Figs. 1 to 4, it will be noted that the bolts 17 are each provided with a longitudinally-extending groove having a straight leading portion 28 and a spirally-curved rear portion 29. Extending into these grooves are lugs 30, which, in this instance, form integral parts of the case 15. As a consequence, it will be appreciated that when the shaft is turned by means of a key or knob the crank 21 will correspondingly move to project or retract the bolt carrier. If the former operation is occurring the bolts will initially have a straight rectilinear movement, incident to the straight portions 28 of the grooves. After these bolts have been projected for a certain distance, however, they will begin to turn, incident to the fact that the lugs 30 are now traversing the spiral portions 29 of the grooves. Thus, as in Fig. 2, the heads 19 of the bolts will have ample opportunity to enter the keeper 31 before they begin their turning movement, and upon full projection and after such entry they will complete a 90° rotation, which will obviously result in the heads extending in a plane at rightangles to the plane which they initially occupied, and if the keeper is provided with an inwardly-extending ledge 32 adjacent its mouth, it will be obvious that no retraction of the bolts from within the keeper could result without turning the bodies of the latter so that their heads will clear this ledge during such retraction.

In the form of lock shown in Figs. 5, 6 and 7, virtually the same form of construction has been resorted to as that shown in the preceding figures, with the exception that the rightangle extension of the bolt carrier is materially thickened, as at 33, and that the ends of the bolts are extended for a considerable distance beyond the rear edge of this portion of the carrier, and at these points are provided with grooves 34 having straight leading and spiral rear portions. Also, the forked portion 19 of the carrier is in this form of lock provided with slots 35

substantially in the line with the grooves 34, and pins 36 are carried by the case 15 and have their bodies extending through these slots, their inner ends projecting into and riding within the grooves 34.

As a consequence, upon the shaft 20 being turned, and the bolt carrier being projected, the bolts 17 will function in the same manner as that in which the bolts of the previously described lock function. However, due to the thickness of the extension 33 it will emerge from the slot 36 and will enter the keeper so that the carrier, in addition to supporting and causing a functioning of the bolts, in itself will act as a "dead-lock" bolt, which, obviously, in certain instances is an extremely desirable factor.

If desired, the lock may take the form shown in Figs. 8 and 9, in which—as has been indicated at 36—the rightangle extension of the carrier is of still greater width than the extension described in the last form. This portion of the carrier, in addition to being bored for the accommodation of the bolts 17, is formed with slots 37 communicating with these bores. The bolts in this form of lock correspond to the bolts shown in Figs. 1 to 4, and the grooves of these elements are engaged by pins 38 carried by the cover-plate 39, which pins extend through the straight slots 37 and into the grooves of the bolts.

Consequently, when the carrier is projected the bolts will accordingly be moved to initially impart to them a straight rectilinear movement and a subsequent turning movement in order to accomplish the results desired. Also, the extension or foot 36 of the carrier will act as a dead-bolt in order to relieve the bolts 17 of strain in the event that relative sidewise movement of the keeper and lock are attempted with the bolt in projected position.

With reference to the form of lock shown in Figs. 10 to 13, it will be noted that the carrier is formed with a rightangle extension or foot 40 bored for the reception of bolts 41, which in this instance are not provided with grooves. The fork 19 of the carrier pivotally supports, as at 42, one end of a lever 43, the inner end of which lies adjacent the inner ends of the bolts 41. These bolts each carry pins 44 eccentrically disposed with respect to their longitudinal axes and projecting from their inner ends. The link 45 is connected with these pins and synchronizes the movement of the bolts, this link being formed with an opening 46 within which the offset end 47 of the lever 43 projects.

This lever is formed with a longitudinally-extending slot 48, which has its rear end 49 extending at an angle to the major portion of its length, and a pin 50 is carried by the case and extends through and rides within

this slot. Thus, upon the carrier being projected the bolts 41, as well as the bolt formed by the foot 40 will have a straight rectilinear movement, but just prior to the completion of the projection the pin 50 will cause the lever 43 to be rocked incident to the engagement of this pin with the angular rear portion 49 of the slot. This will in turn result in the link 45 being moved to rotate the bolts 41 through a 90° angle so that the desired result is again achieved.

In all of the forms which this lock may take the forked end of the carrier may support or be engaged by pins 51 in order to properly confine the movement of the same, and it will be understood that where the ledge 24 is utilized and an attempt is made to forcibly retract the bolt and bolt carriers the resultant strain will not be thrown merely upon the shaft, but that the side edge of the crank will be forced into intimate contact with the ledge so that no danger will exist of the parts becoming distorted.

Finally, it will be appreciated that, while this type of lock preferably includes the ledge, it may be utilized independently thereof, and this latter structure may be employed in locks of other types.

Thus among others, the several objects specifically aforesaid referred to are achieved. It will be appreciated, however, that numerous changes in construction and rearrangement of the parts might be resorted to without departing from the spirit of the invention as defined by the claims.

Having described my invention, what I claim as new and desire to secure by Letters Patent is:

1. A lock, including, in combination, a case, a rotatable crank carried thereby, a bolt operatively connected with said crank to be projected and retracted, a member connected with said bolt and movable with the same and presenting an edge lying adjacent to said crank, and a ledge portion associated with said member adjacent such edge and to be engaged by said crank when the bolt is in projected position to limit the further movement of said crank.

2. A lock, including, in combination, a case, a rotatable shaft, a crank secured thereto, a bolt, a carrier therefor having a forked rear portion straddling said shaft and operatively connected with said crank and a ledge formed adjacent one of the inner edges of said forked portion and to be engaged by one of the side edges of said crank when the bolt is in projected position to limit the further movement of said crank.

3. A lock, including, in combination, a rotatable bolt, a carrier therefor, means for effecting projection and retraction of said carrier, a pin eccentrically disposed with respect to the axis of said bolt and mounted thereon, means associated with said carrier

and connected with said pin for shifting the bolt, and means for operating said last-named means.

4. A lock, including, in combination, a casing, a bolt carrier, a rotatable bolt supported by said carrier, a head at the outer end of said bolt and beyond said carrier, means for shifting portions of said carrier and the bolt supported thereby beyond said casing, and means fixed with respect to the casing for rotating said bolt during such shifting.

5. A lock, including, in combination, a casing, a bolt carrier movable longitudinally of said casing, a pair of rotatable bolts supported by the carrier one to each side of the center of the latter, heads secured to the outer ends of said bolts and beyond said carrier, means for shifting said carrier to have its outer end extended beyond said casing, and means fixed with respect to the casing for rotating said bolts during such shifting.

6. A lock, including, in combination, a casing, a bolt within said casing and extendable beyond the same, a second bolt having a portion disposed in advance of said first named bolt and rotatable with respect thereto, and a means for projecting said first named bolt and effecting a rotation of said last named bolt relatively thereto.

In testimony whereof I affix my signature.

SAMUEL SEGAL.
